UNITED STATES PATENT OFFICE.

JOEL E. WERDA, OF NEW YORK, N. Y.

DESIGN FOR A FONT OF TYPE.

49,660.

Specification for Design.

Patented Sept. 12, 1916.

Application filed July 6, 1916. Serial No. 107,862. Term of patent 14 years.

To all whom it may concern:

Be it known that I, JOEL E. WERDA, a citizen of the United States, residing in the borough of Manhattan, city of New York, and State of New York, have invented a certain new, original, and ornamental Design for a Font of Type for Printing the Syriac Language, of which the following is a specification.

The accompanying drawing which is made a part hereof and to which reference is made, shows the face and form of each letter and character composing said font of type as well as the ornamental character of the font as a whole.

What I claim is:

The ornamental design for a font of type shown in the accompanying drawing, and described.

In witness whereof I have hereunto set my hand at the city of New York.

JOEL E. WERDA.

Witnesses:

GERTRUDE SCHOFIELD,
FRANCES HAYDEN.
